GRATING STRUCTURE

Gerald G. Greulich, Pittsburgh, Pa., assignor to
 Carnegie-Illinois Steel Corporation, a corpora-
 tion of New Jersey

Application May 21, 1934, Serial No. 726,778

2 Claims. (Cl. 72—71)

This invention relates to grating structures, and more particularly to those such as are used for reinforcing heavy duty flooring for decks and bridges, subway or vault covers, loading platforms, 5 and the like.

In constructions of this type, the grating is usually made of metallic elements which are assembled in the field, and subsequently filled with concrete, or other material. Due to the severe 10 usage to which they are subjected, considerable difficulty has been had in attempting to properly distribute the various shearing and bending stresses.

It is one of the objects of the present invention 15 to provide a novel grating structure which will very effectively distribute both positive and negative moment as well as shearing stresses, and particularly those which are directed laterally.

Another object is to provide a novel device 20 of the class described which may be easily and cheaply manufactured, and rapidly installed in the field.

A still further object is the provision of a novel grating structure which will be incapable of moving 25 in any direction with respect to the concrete or other filling material, but one which will at the same time provide free access for the filling material to unite with the object upon which the grating structure rests, if such is desirable.

A still further object is to provide a grating 30 structure comprising horizontal bars which are transversely connected, or "laced", by transverse bars which, when in assembled position, have their upper edges substantially flush or slightly 35 below the upper edges of the longitudinal bars, together with elements which may optionally be used to fill the spaces between the longitudinal bars and thus serve to retain the filling material and thereby prevent its coming into contact with the structure upon which the grating of the invention is adapted to rest.

These and still further objects will be apparent after referring to the drawings, in which:

Figure 1 is a fragmentary plan of the device of 45 the invention.

Figure 2 is an elevation on the line II—II of Figure 1.

Figure 3 is a view on the line III—III of Figure 1.

Figures 4 and 5 are fragmentary details.

Figure 6 is a fragmentary view, partly in section, of another detail.

Figure 7 is an elevation of the device of the invention as used upon the stringers of a bridge 55 floor.

Figure 8 is a view similar to Figure 6 of a further modification.

Referring more particularly to the drawings, the numeral 2 designates the web of the longitudinal bar of the invention, which is provided 5 on its ends with a head 3 and a foot 4. According to one embodiment of the invention, the foot 4 of each of the longitudinal bars is provided on either side with a lateral extension 5.

A plurality of novel L-shaped slots 7 are arranged in the web 2 of each of the longitudinal bars immediately below the head 3, and in such manner as to have their longest portions extending along its axis, which provides a shorter 10 downwardly extending portion 8.

In installing the grating structure, the longitudinal bars are arranged in parallel spaced relationship with their L-shaped slots 7 in substantial alinement.

The transverse or "lacing" bar of the invention is indicated at 9, and is substantially rectangular in cross-section. Each of the transverse bars 9 is provided on one of its edges with a plurality of recesses 10 having sloping side walls, as at 12. The side walls 12 of the recess 10 conform substantially to a portion of the head 3 of the longitudinal bars.

In installing the transverse bars 9, they are inserted through the longest portions of the L-shaped slots 7, until the various recesses 10 are 20 immediately below the heads 3 of the longitudinal bars. The transverse bars 9 are then rotated approximately 90 degrees which permits the side walls 12 of the recesses 10 to engage the sides of the heads 3 of the longitudinal bars, and the 25 upper edges of the transverse bars 9 will be approximately, if not exactly, flush with the upper edges of the longitudinal bars.

The transverse bars 9 are welded to the longitudinal bars while in this position, as indicated at 30 40 45 50 55 60 65 70 75 80 85 90 95 100 105 110 115 120 125 130 135 140 145 150 155 160 165 170 175 filling material between the various bars from coming into contact with the structure upon which the longitudinal bars rest, and for this purpose a plurality of plates 19 are provided.

5 These plates 19 are of a width substantially equal to the distance between the feet 4 of the longitudinal bars, and are provided on either side with an upward extension 20 which permits them to rest on the lateral extensions 5. The upwardly 10 extending ends 20 of the plates 19 may, if desired, be welded to the feet 4 of the longitudinal bars, as indicated at 22.

The preferred embodiment of the invention 15 contemplates a plurality of transverse bars 24 which are adapted to be "laced" between the longitudinal bars adjacent their feet 4. These lower transverse bars 24 are provided with recesses 25 which conform substantially to the upper portions of the feet 4 of the longitudinal bars, and 20 are further provided with sloping side walls 26 to permit them to clear the upward extensions 20 of the plates 19. The webs 2 of the longitudinal bars are provided with L-shaped slots 28 which are positioned close to the feet 4 with their long- 25 est portions extending along the axes of the webs in such manner that their shortest portions extend upwardly, as at 29.

In order to more thoroughly distribute the 30 shearing stresses of the grating structure the lower transverse bars 24 are arranged alternately with respect to a horizontal plane through the upper transverse bars 9. The manner of installing the lower transverse bars 24 is identical with that previously described for the transverse 35 bars 9.

Referring to Figure 6, an abutment is provided for the sides of the outer longitudinal bars of the grating. These abutments are composed of angles 30, having one of their edges welded along 40 the feet 4 of the longitudinal bars, as shown at 31.

It is preferable to permit the upper and lower transverse bars 9 and 24, respectively, to extend 45 beyond the outer longitudinal bars and to come in contact with the angles both along their faces 32 and a portion of their upstanding ends, as shown at 33. The upper and lower transverse bars 9 and 24 may, if desired, be additionally welded to the angles, as at 34.

50 In Figure 7 of the drawings, the grating structure is intended to rest upon stringers 35 of a bridge floor. The longitudinal bars are welded to the stringers 35, as shown at 36, and the plates 20 are made to extend onto them for a short distance, as shown at 37. If desired, the plates 55 20 may also be welded to the stringers, as shown at 38.

Referring to Figure 8, a modified longitudinal bar is illustrated as comprising a web 2, and identical head and foot portions 40, which are grooved on either side to accommodate the upward extensions 20 on the plates 19. In this form, the longitudinal bars may be used with either end up. 5

Another modification contemplates the overlapping of the ends of the upper and lower transverse bars 9 and 24, respectively. This is illustrated in Figures 1 and 2, having been done to the lower transverse bars 24, the ends of which have been bent away from each other as at 46. These ends may be welded together, as at 48, to provide greater rigidity.

While I have shown and described several specific embodiments of my invention, it will be understood that I do not wish to be limited exactly thereto, since various modifications may be made without departing from the scope of my invention, as defined by the following claims. 15 20

I claim:

1. In a grating structure, a plurality of I-bars in spaced parallel relation, the webs of said I-bars being provided with aligned apertures adjacent their respective head and foot portions, and substantially rectangular transverse bars disposed to extend through the apertures of adjoining I-bars, the outer edges of the assembled transverse bars being notched to conform substantially to the section of the respective head and foot 30 portions of said I-bars, the inner edges of the assembled transverse bars being uninterrupted, said notches being of sufficient depth to permit the outer edges of the assembled transverse bars to occupy substantially the same plane as the 35 outer edges of the respective head and foot portions of said I-bars.

2. In a grating structure, a plurality of I-bars in spaced parallel relation, the webs of said I-bars being provided with aligned apertures adjacent 40 their respective head and foot portions, substantially rectangular transverse bars disposed to extend through the apertures of adjoining I-bars, the outer edges of the assembled transverse bars being notched to conform substantially to the 45 section of the respective head and foot portions of said I-bars, the inner edges of the assembled transverse bars being uninterrupted, said notches being of sufficient depth to permit the outer edges of the assembled transverse bars to occupy substantially the same plane as the outer edges of the respective head and foot portions of said I-bars, and a plate extending between the foot 50 portions of adjacent I-bars.

55 GERALD G. GREULICH.
